(57) **CLAIM**

The ornamental design for a meat fluid injector, as shown and described.

DESCRIPTION

FIG. 1 is a front perspective view of a meat fluid injector, showing my new design;

FIG. 2 is a front elevation view thereof;

FIG. 3 is a top plan view thereof;

FIG. 4 is a left-side elevation view thereof;

FIG. 5 is a right-side elevation view thereof, and,

FIG. 6 is a bottom plan view thereof.

The broken lines in the drawings depict portions of the meat fluid injector that form no part of the claimed design.
